No. 36,710.

Patented December 29, 1903.

UNITED STATES PATENT OFFICE.

JACINTO M. NAVARRO, OF NEW YORK, N. Y.

DESIGN FOR A NAME-PLATE FOR COFFEE-MILLS.

SPECIFICATION forming part of Design No. 36,710, dated December 29, 1903.

Application filed November 28, 1903. Serial No. 183,072. Term of patent 14 years.

To all whom it may concern:

Be it known that I, JACINTO M. NAVARRO, a citizen of the United States, residing at the city of New York, county of New York, and State of New York, have invented a new, original, and ornamental Design for the Name-Plate of a Coffee-Mill, as shown in the accompanying drawing, said drawing being a face view of my newly-designed name-plate.

10 What I claim is—
The ornamental design for the name-plate of a coffee-mill, as shown in the accompanying drawing.

In testimony that I claim the foregoing as my invention I have signed my name, in presence of the subscribing witnesses, this 27th day of November, 1903.

JACINTO M. NAVARRO.
